UNITED STATES PATENT OFFICE.

GEORGE ORVILL TERRY, OF MINNEAPOLIS, MINNESOTA, ASSIGNOR TO ECONOMY SHOE MACHINERY COMPANY, OF MINNEAPOLIS, MINNESOTA, A CORPORATION OF MINNESOTA.

EDGE-SCOURING ROLL.

1,387,627.

Specification of Letters Patent. Patented Aug. 16, 1921.

Application filed September 7, 1920. Serial No. 408,608.

To all whom it may concern:

Be it known that I, GEORGE ORVILL TERRY, a citizen of the United States, residing at Minneapolis, in the county of Hennepin and State of Minnesota, have invented certain new and useful Improvements in Edge-Scouring Rolls; and I do declare the following to be a full, clear, and exact description of the invention, such as will enable others skilled in the art to which it appertains to make and use the same.

My present invention has for its object to provide an improved edge scouring roll especially adapted for use in finishing sole edges, in shoe factories and repair shops, and to such ends, generally stated, the invention consists of the novel devices and combinations of devices hereinafter described and defined in the claims.

20 In the accompanying drawings, which illustrate the invention, like characters indicate like parts throughout the several views.

Referring to the drawings:

Figure 1 is an axial section of the improved edge scouring roll;

Fig. 2 is a section on the line 2—2 of Fig. 1; and

Fig. 3 is a view corresponding to Fig. 2, but showing the two-part wheel opened up.

30 The complete scouring roll comprises two disk-like flanges preferably having hubs secured to a driving shaft or spindle, and a diametrically split or two-part wheel. The wheel sections may be variously formed integral or otherwise, and as shown, each half-wheel section comprises a semi-annular wooden body 4 and metallic, preferably cast, disk-like cam plates 5 rigidly secured thereto, as shown by means of screws 6. The two wheel sections 4 are connected by a hinge 7, and one of the wheel sections is provided with laterally spaced rings 8 preferably formed integral with its cam plates 5. These rings 8 are of a size to closely fit the 45 driving shaft 9.

The cam plates 5, in their outer faces, are formed with eccentric cam grooves 10, but here it may be stated that these cam grooves are only necessary in the cam plates of the 50 outwardly swinging wheel sections, but are shown as provided in the cam plates of the other wheel section because, in practice, the cam plates are first made as complete disks

and then sawed diametrically to form the sections.

The flanges 11, noted above, are disk-like elements with flat inner faces and outstanding hubs 12 that are rigidly secured to the shaft 9 by set screws 13. The flat faces of the flanges 11 are so spaced that the wheel 60 sections fit closely between the same. For coöperation with the cam grooves 10 of the out-swinging wheel section, the flanges 11 are provided with alined inwardly projecting cam pins or studs 14.

When the closed wheel is turned so that the cam pins 14 are close to the free portions of the outswinging wheel section, the latter may then be freely swung to its open position shown in Fig. 3. The periphery 70 of the two wheel sections 4 are provided, preferably, with pliable facings 15 that are covered with the scouring cloth or paper 16, the ends of which are turned inward between the wheel sections, as shown in Fig. 2, when the wheel is closed. To securely hold these inturned ends of the cloth or paper 16, the wheel sections are provided with barbs 17 and barb seats 18.

As is evident, when the wheel is opened 80 up as shown in Fig. 3, the scouring cloth or paper may be readily removed and replaced with new scouring cloth or paper.

When the wheel sections have been closed, the closed wheel should be turned in the direction of the arrow marked on Fig. 2, so as to cause the cam pins 14 to act on the inner portions of the cam grooves 10 and thereby cam the wheel sections together.

In applying the wheel section that has the 90 rings 8 thereon, to the shaft, attention must be paid to the direction in which the shaft, see Fig. 3, will rotate when in action, and said wheel must be applied in such a manner that when the shaft is rotated, the backward 95 driving action on the wheel due to the friction, will tend to rotate said wheel in a direction to cause the cam pins 14 to more tightly close the wheel sections together.

A further important novel feature should 100 be noted, to wit; that the quite sharp, but slightly rounded peripheral edges of flanges 11 project beyond the applied scouring cloth or paper, so that the one or the other thereof, in finishing a shoe sole, will always be between the shoe sole and the shoe upper or

leather body and will positively prevent defacing of the latter by keeping the same out of contact with the abrading surface of the scouring cloth or paper.

5 It is important to note that the projecting peripheral portions of the two hub flanges are smooth and unbroken so that there are no rough or sharp edge portions that can cut or damage the leather of the shoe upper even if it should come in contact therewith. Obviously, cam slots or the like running to the edges of the hub flanges would produce cutting portions that would cut the leather if coming in contact therewith.

10 15 What I claim is:

1. An edge scouring roll comprising laterally spaced axially alined rigidly connected rotary hub flanges, at least one of which has a lateral cam projection, and a split scouring wheel one section of which is rotatively mounted between said flanges and the other section of which is movable to and from working position and is provided on at least one side with a cam surface, which under rotation of the closed wheel coöperates with 20 25 said cam projection to lock the two wheel sections together.

2. An edge scouring roll comprising laterally spaced axially alined rigidly connected rotary hub flanges, at least one of which has a lateral cam projection, and a split scouring wheel one section of which is rotatively mounted between said flanges and the other section of which is movable to and from working position and is provided on at least one side with a cam surface, which under rotation of the closed wheel coöperates with 30 35 said cam projection to lock the two wheel sections together, the peripheral edge of at least one of said flanges projecting beyond the periphery of the closed wheel.

3. An edge scouring roll comprising laterally spaced axially alined rigidly connected rotary hub flanges, at least one of which has a lateral cam projection, and a split scouring wheel one section of which is rotatively

50 mounted between said flanges and the other section of which is movable to and from working position and is provided on at least one side with a cam surface, which under rotation of the closed wheel coöperates with 55 said cam projection to lock the two wheel sections together, the peripheral edge of at least one of the said flanges projecting beyond the periphery of the closed wheel, said projection being smooth and unbroken.

4. A scouring roll comprising laterally spaced axially alined rigidly connected rotary hub flanges, and a split scouring wheel one section of which is rotatively mounted 60 between said flanges and the other section of which is movable to and from working position, said flanges having opposing cam projections and said movable wheel section having eccentric cam surfaces with 65 which said cam projections are engageable, under rotation of the closed wheel, to lock the two wheel sections together and to said flanges.

5. A scouring roll comprising laterally spaced axially alined rigidly connected rotary hub flanges, and a split scouring wheel one section of which is rotatively mounted between said flanges and the other section of which is movable to and from working 70 75 position, said flanges having opposing cam projections and said movable wheel sections having eccentric cam surfaces with which said cam projections are engageable, under rotation of the closed wheel, to lock the 80 wheel sections together and to said flanges, the peripheral edges of the said flanges being smooth and unbroken and projecting beyond the periphery of the closed wheel.

6. A scouring roll comprising a scouring 85 wheel and hub flanges on the opposite sides thereof and said hub flanges having smooth unbroken peripheral edges that project beyond the periphery of said wheel.

In testimony whereof I affix my signature.

GEORGE ORVILL TERRY.
